UNITED STATES PATENT OFFICE.

WALTER FERRIER, OF ELYRIA, OHIO, ASSIGNOR TO THE ELYRIA IRON AND STEEL COMPANY, OF CLEVELAND, OHIO, A CORPORATION OF OHIO.

CONTROL DEVICE FOR AUTOMATIC MACHINES.

1,385,369.

Specification of Letters Patent. Patented July 26, 1921.

Application filed October 11, 1919. Serial No. 330,113.

To all whom it may concern:

Be it known that I, WALTER FERRIER, a citizen of the United States, residing at Elyria, in the county of Lorain and State of Ohio, have invented certain new and useful Improvements in Control Devices for Automatic Machines, of which the following is a specification.

My invention relates to control devices for automatic machines such as machines for cutting metal bars, strips, rods and other metal stock to given lengths. For instance, my invention may well be embodied in a machine for straightening strip steel stock and cutting it into predetermined, selected lengths, and I have so illustrated it in the drawings hereof.

One of the objects of my invention is to provide a construction whereby the shearing of the metal stock may be accomplished with the greatest accuracy to insure that all cut sections will be of length falling within very small limits of tolerance; substantial or practically-exact uniformity of length being easily attainable by the use of my invention. A further object is to provide control devices that, in all parts, are of simple, economical and rugged form and construction, insuring low cost, and constancy and uniformity of efficient performance with minimum care.

To these ends, and for other advantages which will become apparent from the following description, my invention consists in the features of construction and combinations of parts touching the automatic control and the association thereof with the machinery as hereinafter set forth and claimed.

In the drawings Figure 1 is a plan view of the machine embodying my invention; with parts broken away; Fig. 2 is a diagrammatic view showing some parts in plan and other in elevation, and illustrative particularly of the control equipment; Fig. 3 shows a clutch-detail and Fig. 4 shows a switch-detail.

In the particular machine shown the stock A, such as steel strip, initially coiled, is to be fed, as by rolls 10', through the straightening rolls 10, past the shears or cutting instrumentality 11, onto the dump-table 12 and the shears 11 are to be operated when an accurately-prescribed length of the stock has been passed between them. A motor,

13,—constantly running when the machine is in operation,—may be clutch-connected with, or disconnected from, the gearing for the straightening rolls 10, and feed rolls 10', and a brake 14 may be applied to stop the rolls abruptly as soon as the clutch is disconnected. From a suitable source of power, preferably a second motor 16,—constantly running when the machine is in operation,—a cam shaft 17 may be driven, on occasion, through the intermediary of a positive clutch. This cam shaft carries the eccentric 18 or other suitable means by which the shears 11 are operated, and also a face cam 19 by which, through the linkage connection generally indicated at 20 the laterally tiltable table 12 may be caused to dump against the resistance of a counter-weight 21 that holds it normally in horizontal position.

Specifically, motor 13 has a pinion 23 meshing with a large gear 24 that is axially and rotatively loose on a shaft 25, this gear having a friction-clutch rim 26. A coiled spring 27 interposed between the gear and the shaft-bearing 28 tends to maintain the gear in clutch engagement with a clutch-cone 29 that is rigidly keyed as at 30 to the shaft 25 and is provided with a brake drum 31 for coaction with the brake-band 14. Pins 33 slidingly extending through said clutch cone, are fixed at one end in a slidable collar 34 that surrounds the shaft, and at their other end these pins bear against the hub of the axially shiftable gear-and-clutch member 24. When shifter lever 35 that engages collar 34 is thrown toward the motor, it pushes the slidable clutch element 24 out of engagement with the fast clutch element 31, so disconnecting the motor from the main shaft 25. At the same time, through suitable linkage 36 the shifter lever 35 applies the brake 14, promptly to stop rotation of the shaft 25 and of the feed rolls 10' geared thereto. The shaft 25 has suitable connection through further reduction gearing with the gear train of the straightening-roll set 10 and the feed rolls 10'.

Thus the machine has a power source, a clutch-controlled drive for feed rollers, a brake for the feed-parts and means simultaneously to disconnect the feed rolls from the power source and apply the brake.

Cam shaft motor 16 drives a reduction

gear train 40 communicating motion to a constantly-rotating gear 41, the hub of which has one or more teeth (preferably four) in the form of circumferentially spaced laterally-extending pins 43. This gear 41 is loose on the cam shaft, and said shaft carries a clutch bar 45 movable to connect or disconnect the shaft relative to the gear 41. This bar 45 is mounted to slide 10 axially in a slot in the shaft and is pressed by spring 46 toward the clutch pins 43 so that, when freed from restraint, it will be spring-projected into the path of rotation of said clutch pins 43 positively to connect 15 the shaft to the constantly rotating gear 41. The clutch bar 45, however, has a suitably beveled head 47 projecting radially from the shaft-slot that may, in rotation, strike a latch arm 48 having a correspondingly beveled end, this latch arm being pivoted as 20 at 49 on the frame of the machine so that it may be moved into and out of head-engaging position. Under the influence of a weighted lever 50 the latch arm is normally 25 positioned so that it holds the clutch bar 45 retracted, but when the free end of lever 50 is raised, latch 48 is thrown out of the path of, and out of engagement with, the head of clutch bar 45, allowing the latter to be projected into the path of movement of pins 43 as aforesaid. The gear 41 then rotates 30 the cam shaft, but if, prior to the completion of the cycle of rotation of the cam shaft, latch arm 48 is allowed to be weight-re- 35 turned to normal position, its beveled end intercepts the head of the clutch bar so that the latter is retracted and the cam shaft brought to rest after its single rotation. Thus, the cutting instrumentalities and cup- 40 strip dumping-table are actuated from a cam-shaft clutch-connectible with a constantly driven member, such as gear 41. I do not claim any novelty in any part of the machine thus far specifically described; 45 this being but one construction to which my control devices may advantageously be applied.

Heretofore it has been the practice, in machines of the kind described, to control 50 the shifter-lever 35 for the main-shaft clutch by a cam on the cam-shaft, and to control the lever 50 for the cam-shaft-clutch latch 48 by a mechanical connection with a finger disposed in the path of travel of the end of 55 the stock strip. Such arrangement has resulted in inaccuracies of length because, although the stock may trip the latch 48 with tolerable accuracy, the cam shaft may be picked up by the running wheel 41 any- 60 where within a quadrant turn of that wheel,—*i. e.*, anywhere within the angular separation of the pins on the wheel hub, and since the feed continued during this indeterminate interval, length variations of 65 serious consequence in the strips cut off were

inevitable. By the application of my invention I obviate this inaccuracy of strip-length.

The controlling mechanism of my invention as applied to such a machine comprises 70 means, preferably electrical and herein illustrated as a solenoid 51, horizontally mounted on the frame, and having its core directly acting on the shifter lever 35 to control the clutch and brake; means herein illustrated 75 as solenoid 52, vertically mounted on the frame and having its core connected for directly acting on the cam-shaft-clutch controlling-lever 50; and means, herein illustrated 80 as an electric switch 53 and appurtenant appliances, operatively associated with the dump-table to be controlled by the length of the stock delivered past the shears, and controlling the energization of both 85 said solenoids 51 and 52. Thus, solenoid 51—which, when energized, directly throws the shifter lever 35 to unclutch the main-shaft from its driving means and apply the feed-roll-stopping brake—and solenoid 52—which, when energized, directly lifts the 90 cam-shaft clutch-controlling lever 50 to throw the latch arm 48 out of engagement with the clutch bar 45, permitting the latter to clutch the normally idle cam shaft of the 95 constantly driven wheel 41, are arranged in parallel branches of a power circuit 54, suitably energized, and controlled from the switch 53. Preferably I provide a relay 56, the armature of which is normally retracted to open the power circuit and the coil of 100 which is included with the switch 53 in a suitable branch circuit. Switch 53, functioning when closed to complete the circuit for the relay magnet, may be a single-pole single-throw spring switch with an operating arm extending into the path of movement of the metal stock so that the stock will strike against and close the switch, which will be reopened by its spring, as soon as the dump-table is dropped and dislodges 110 the cut strip. To permit the strip length to be varied the switch 53 has its base-plate 57 adjustably mounted on a fixed rail 58 above the table, and secured as by set screws 59. The operating arm 60 preferably has at 115 its lower end a slide-plate 61 of fiber or other insulation that rides on the table as the arm is swept through its operative arc, this plate having a slot 62 to receive guide- 120 stud 63. This construction assures that the switch may be actuated accurately and without failure, whether the stock be thick or thin, wide or narrow.

In the operation of the machine the steel strip, fed forwardly by the rollers 10, travels between the shears and along the tilt-table 12 until its forward end, making contact with the switch arm, moves the latter to close the switch 53. Instantly relay 56 closes the main circuit, energizing both 130

solenoids 51 and 52 so that at the same moment solenoid 51 throws shifter lever 35 to unclutch the main motor 13 from driving relation with the rolls 10, 10', and apply the brake instantly to stop said rolls, while solenoid 52 works through lever 50 to throw out the latch 48 which theretofore has been maintaining the cam shaft unclutched from the constantly rotating wheel 41. Of course, the positive clutch pin or pins 43 of the said wheel may not at that moment be in position to pick up the clutch bar 45 of the cam shaft, and an appreciable time may elapse before the shear operates to sever the strip, but owing to the stoppage of the feed mechanism independently, through its solenoid 51, this does not result in any error in the length of material cut. Of course, as soon as the shears have completed the cutting of the material the positive action of the cam 19 on shaft 17 causes the table 12 to dump the severed strip, thereby releasing switch 53 which springs back to normal or open position, permitting the armature of relay 56 to be spring retracted, deenergizing both solenoids, so that the shifter lever 35 for the main clutch is spring-thrown to normal position as the clutch gear wheel 24 is forced axially along its shaft by spring 27, and lever 50 for the cam shaft clutch is weight-depressed, throwing the latch arm 48 into elevated position again, where, as the clutch bar 45 completes the rotative excursion in which it is then engaged, said latch intercepts the clutch bar, camming it back to unclutched position and stopping the rotation of the cam shaft in normal station. The tilting table meanwhile is weight-returned to normal position and the machine is ready for a second cycle of operation.

While I have herein described in some detail a particular embodiment of my invention, it will be understood by those skilled in the art that changes in the details of construction and arrangement might be made without departure from the spirit of my invention within the scope of the appended claims.

I claim:

1. In a machine of the character described, the combination of stock feeding mechanism, a clutch therefor, a lever directly acting on said clutch for moving it to disabled position and a brake actuated by said lever for stopping said feed mechanism, an electro-magnet for throwing said lever to braking position, a cam shaft mechanism, a clutch therefor, a stock cutter actuated by said cam shaft mechanism, a detent mechanism normally holding said clutch for the cam shaft mechanism out of operation and movable to permit the clutch to act, an electro-magnet for operating said detent mechanism and an electric switch in the path of the said stock having connections with both said magnets simultaneously to energize the same, whereby said magnets positively and independently control the respective mechanisms aforesaid.

2. In a machine of the character described, the combination of feed mechanism, a constantly rotatable driving member, a clutch for connecting said driving member and feed mechanism, a brake for stopping the feed mechanism, a lever for disconnecting said clutch and applying said brake, an electro-magnet connected with said lever to impart braking operation to the latter, a cam shaft, a constantly rotatable member for driving said cam shaft, clutch means for connecting said member and cam shaft, a detent for maintaining said clutch member normally inactive and movable to condition said clutch to act, an electro-magnet for moving said detent, directly connected thereto, shear mechanism and a cut-box dumping table both actuated by the cam shaft, a switch associated with said dumping table in the path of movement of the fed stock, and circuit connection from said switch in parallel to the said two magnets, for simultaneously energizing and de-energizing the same.

WALTER FERRIER.
